UNITED STATES PATENT OFFICE.

RUBY T. BREWSTER, OF NEW YORK, N. Y.

DESIGN FOR A BOTTLE OR SIMILAR CONTAINER.

Application filed April 6, 1927. Serial No. 21,488. Term of patent 3½ years.

To all whom it may concern:

Be it known that I, RUBY T. BREWSTER, a citizen of the United States, residing at New York city, in the county and State of New York, have invented a new, original, and ornamental Design for a Bottle or Similar Container, of which the following is a specification, reference being had to the accompanying drawing, forming part thereof.

The figure is a perspective view of a bottle or similar container, showing my new design.

I claim:

The ornamental design for a bottle or similar container, as shown.

RUBY T. BREWSTER.
